UNITED STATES PATENT OFFICE.

THEODORE A. SCHRAISHUHN, OF CORAOPOLIS, PENNSYLVANIA, ASSIGNOR TO LEWIS
FOUNDRY & MACHINE COMPANY, A CORPORATION OF PENNSYLVANIA.

ROLLING MILL.

Application filed February 25, 1927. Serial No. 170,833.

This invention relates to a driving connection for a rolling mill, and particularly to a driving connection for a rolling mill constructed in accordance with my Patent No. 5 1,638,463, dated August 9, 1927.

Such mill is particularly designed for the cold forming of metallic shapes by bending the stock metal; and such mill is operated as a continuous mill, the stock being progressively formed in the successive passes thereof. For various classes of work it is therefore desirable that such mill comprise a greater number of pairs of die spindles than is necessary for other classes of work. For this 15 reason it is of advantage that the general arrangement of the mill be by units, so that a greater or lesser number of die spindles may be provided in a machine without alteration in the fundamental design of the machine as 20 a whole, and that the general machine assembly may be adapted to various classes of work by the addition or removal of one or more units.

It is desirable in such mill to so arrange 25 the driving connections and housings of each unit that the die spindles of the unit are held against horizontal movement in one direction, and relative displacement of the driving gears avoided without the provision of locking collars, or similar fastening means.

The patent, above noted, provides a double helical gear in the driving connections, this double helical gear rendering the pinions for the upper and lower spindles interchangeable, and serving to direct inwardly the driving 35 thrust on the lower spindles. This direction of the driving thrust prevents any unmeshing of the lower pinions from the gear, and prevents any undesired horizontal movement of the lower spindles. Outward movement of the upper pinions and spindles is avoided by linkage which primarily serves 40 for centering the upper pinions and the idlers which connect such pinions with the driving gear.

The object to the present invention is to prevent strain on such linkage by use of a driving gear, capable of meshing with both the lower and upper pinions, which directs 45 the driving thrust inwardly on both pairs of pinions and the spindles which carry them.

In the accompanying drawings Figure 1 is a horizontal sectional view through one of the units comprised in a forming mill of the

above noted type; Figure 2 is a detail plan 55 view of the immediate driving connections for the spindles of the unit; Figure 3 is a detail elevation of the structure shown in Figure 2; Figure 4 is a central cross sectional view through the unit; and Figure 5 is a 60 detail rear elevation, showing parts of two spindle stands.

The unit as a whole is mounted on a base or table 1; and comprises a rear housing formed of two U-shaped stands 2, and a front 65 housing 3 comprising two U-shaped stands 4. The U-shaped stands 4 may be connected by any suitable members, such as the seating members 3^a and the bolted bracket 3^b shown in Figure 5. Bearings 5 and 6 for the upper 70 spindles 7 and lower spindles 8 respectively are supported by the front and rear stands of the unit.

The spindles of the unit are driven from a line shaft 9. At the rear of the unit is a 75 casing 11 which is secured to the stands forming the rear housing of the unit, and which contains the immediate driving connections for the spindles of that unit. Such immediate driving connections comprise a 80 unit driving shaft 12, which carries a worm gear 13, meshing with a worm 14 on the line shaft 9.

The unit driving shaft 12 carries a wide helical gear 15. Driving gears 16 and 17 85 have the two lower spindles 8 meshing with the helical gear 15 toward its outer edge; while idler pinions 18 and 19, meshing in turn with driving gears 20 and 21 on the upper spindles 7, mesh with the inner portion 90 of the helical gear 15. Both the driving gears 16 and 17, and the idler pinions 18 and 19, are of a width less than half the width of the helical gear 15. This is necessary for an adjustment which will be hereinafter described.

Bearings 5 are vertically adjustable by means of adjusting screws 22, which are shown as of usual form. In order that the centers of the idler gears 18 and 19 and 100 upper spindle gears 20 and 21 may be aligned irrespective of the adjustment of the upper spindles, special mounting means are provided for the idlers. Such mounting means comprise brackets 23 and 24, which are free 105 on the unit drive shaft 12. These brackets provide bearings for the shafts 25 of the idlers 18 and 19. On shafts 25 are links 26

and 27, which are secured to the extremities of the spindles 7.

The idler mounting arrangement provides for the adjustment of the upper spindles 5 without affecting the relative centers of their driving gears. Due to the fact that all of the pinions are of a width no more than half that of the main driving gear, the pinions 20 and 21 may be so lowered that 10 they overlap the pinions 16 and 17. This provides for an adjustment of centers for any forming dies which it may prove desirable to employ in a unit.

In order to prepare a unit for the particular work to be done, it is merely necessary to loosen bolts 30 in a cover plate 4^a and slide the housings 4 completely off the table 1. The dies are then slid onto the spindles 7 and 8, and the front housings replaced. In replacing a front housing stand 20 4 slides rearwardly of the spindles on the guide strips 29, and is locked in proper position with respect to the dies by means of fastening bolts 30. In each unit the front 25 housing, comprising the two stands 4, may be adjusted as a whole; or the stands may be adjusted one at a time by removing bolts 33 in bracket 3^b, and loosening bolt 30.

The dies may thus be readily applied to 30 the spindles, and the front housing transversely adjusted with respect to the rear housing and dies without the use of spacing collars or other spacing means.

When the main driving gear 15 is rotated 35 in a counter clockwise direction, the driving thrust is directed inwardly of the spindles toward the front housings. For this reason there is no necessity for using locking collars or the like to prevent rearward movement of the spindles in the housings. There 40 are therefore no locking means between the rolls and the front stands to be unfastened as a preliminary step in adjusting the front stands 4 toward and from the rear stands 2. Further since the driving thrust is inward 45 of both the lower spindles 7 and the upper spindles 8, there is no strain on the links 23, 24, 26, and 27, any tendency toward any 50 unmeshing of the gears being avoided by the direction of the driving thrust. The use of the helical gear and helical pinions also permits the speed of the rolls to be accurately timed, since there is no play caused by back lash between the gears. This latter is of 55 greater advantage where the dies carried by a number of opposed upper and lower rolls are not identical, but cooperate with each other in a certain definite manner to effect

indentation of the stock in the forming operation.

What I claim is:

1. In a forming mill the combination of a base, a pair of housings on said base, a pair of cooperating spindles in said housings, a driving shaft, a relatively wide helical gear on said driving shaft, a pinion on the spindle meshing with the helical gear and of a width less than one-half the width of said gear, a bracket freely mounted on the driving shaft, a shaft in said bracket, a link connecting said shaft with the other spindle, an idler pinion on said bracket shaft and meshing with the helical gear, and a pinion on the spindle having teeth with a helix opposite to those of the other pinion, and having a width less than one-half the width of the helical gear meshing with said idler pinion to permit movement thereof past the pinion on the other spindle. 60

2. In a forming mill the combination of a base, a pair of housings in said base, a pair of cooperating spindles in said housings, a driving shaft, a relatively wide gear on said driving shaft, a pinion on one spindle meshing with the driving gear and of a width less than one-half the width of said gear, a bracket freely mounted on the driving shaft, a shaft in said bracket, a link connecting said shaft with the other spindle, an idler pinion on said bracket shaft and meshing with the driving gear, and a pinion on the spindle having teeth with a helix opposite to those of the other pinion, and having a width less than one-half the width of the driving gear meshing with said idler pinion to permit movement thereof past the pinion on the other spindle. 65

3. In a forming mill the combination of a base, a pair of housings on said base, one of said housings being mounted for movement transversely of the base, a pair of cooperating and vertically spaced spindles in said housings, a driving shaft, a relatively wide helical gear on the driving shaft, and helical pinions of a width less than one half that of the driving gear mounted on the spindles and driven from the gear, the tooth helix of the pinions being opposite and the helix of the several pinions being so arranged with respect to the direction of rotation of the driving gear that the driving thrust on both is directed toward the transversely movable housing. 70

In witness whereof, I hereunto set my hand.

THEODORE A. SCHRAISHUHN.
